Primary Examiner — Sheryl Lane*Assistant Examiner* — Mark T. Philippss(74) *Attorney, Agent, or Firm* — Quickpatents, LLC; Kevin Prince(57) **CLAIM**

The ornamental design for a double cutting die, as shown and described.

DESCRIPTION

FIG. 1 is a perspective view of a double cutting die, showing my new design;

FIG. 2 is a top plan view of FIG. 1;

FIG. 3 is a bottom plan view of FIG. 1;

FIG. 4 is an enlarged left-side elevation view of FIG. 1, the right-side elevation view being a mirror image thereof; and, FIG. 5 is an enlarged cross-sectional view taken along line 5-5 of FIG. 2.

The dot-dash broken lines represent a boundary of the claimed design. The remaining broken lines depict portions of the double cutting die that form no part of the claimed design.
